UNITED STATES PATENT OFFICE.

SAMUEL THOMAS WALKUP, OF NEW YORK, N. Y.

CAR-DOOR.

1,379,583.

Specification of Letters Patent. Patented May 24, 1921.

Application filed September 6, 1919. Serial No. 222,047.

To all whom it may concern:

Be it known that I, SAMUEL THOMAS WALKUP, a citizen of the United States of America, residing at 875 West 180th street, city of New York, borough of Manhattan, State of New York, have invented new and useful Improvements in Car-Doors, of which the following is a specification.

This invention relates to a control system for passenger car doors, having more particular reference to an electrical control system, and being intended more particularly for application to city transit trains such as subway or elevated trains.

15 The invention has for a general object to provide an improved and simplified control system whereby the doors of a plurality of cars may be operated in unison, thus reducing the number of guards required on each 20 train.

More specifically speaking the invention has for an object to provide a control system whereby the platform men at the stations may operate the doors, and whereby the 25 number of cars controlled by a single platform man may be varied as desired.

For further comprehension of the invention, and of the objects and advantages thereof, reference will be had to the following description and accompanying drawings, and to the appended claims in which the various novel features of the invention are more particularly set forth.

Figure 1 of the drawings is a side elevation of a portion of a train adapted to be controlled by my system, indicating it in engagement with the coöperating station equipment.

Fig. 2 is a diagrammatic view showing 40 the electrical connections.

Fig. 3 is an enlarged end elevation, indicating also a portion of the station.

Fig. 4 is a detail side elevation of the contact member carried by the train showing 45 also a portion of the fixed station contact with which it engages.

Fig. 5 is a fragmentary detail indicating the door operating means.

Fig. 6 is a detail horizontal view of the 50 control adjustment device.

In the drawings the reference numeral 1 indicates in general a passenger car such as is in common use in underground city transit systems which are generally known as "sub-

ways." In Fig. 1 I have shown one complete car and a portion of two adjoining cars and in Fig. 2 I have indicated a ten car train. The car wheels are indicated at 2 and the track rails at 3.

In the present instance each car is provided on each side with a center door 4 and end doors 5 of the usual sliding type. The precise means for operating those doors forms no part of the present invention, my improved control system being applicable to any electrically operated or controlled mechanism for operating the doors. For purposes of illustration I have indicated a door operating means in Fig. 4 comprising an air cylinder 6 to one end of which a pipe 7 connects, this pipe leading from a two way valve 8, controlling an air supply pipe 9. The valve is operated by a solenoid 10, whose core 11 is connected to the valve handle 12 by a link 13. A piston 14 slides in cylinder 6 and operates a piston rod 15 whose outer end engages in a slot 16 in a lever 17 fulcrumed on a fixed part of the car and engaging in a slot formed by a strap 18 on the side of the door, this operating means being duplicated for each door. A spring 19 returns the solenoid core 11 to position holding the exhaust passage of the valve 8 open, while a spring 20 in cylinder 6 causes the door to close when the air pressure is removed from the piston 14.

My improved control system comprises a series of contact rails 21 which are located at the stations above the tracks and at a sufficient height to clear the cars, being secured to any suitable part, in this case the roof 22 of the subway station. These rails are preferably approximately the length of a car, and a number thereof equal to the maximum number of cars in a single train are stretched in sequence as shown, their ends being upturned as at 23 and spaced a sufficient distance apart to insulate them from another.

In the present instance I have shown ten of these rails to accommodate a ten car train and from these rails wires 24 lead, one wire from each rail. The opposite ends of these wires lead to a control adjustment device which may be in the form of a box 25 carrying an insulating block 26 on which are mounted a plurality of bars 27 each having a series of sockets 28 equal in number to

the number of contact rails. Each of these wires terminates in loose portion 29 carrying a plug 30 adapted to engage in any of the sockets. From these bars wires 31 lead 5 through a battery 32, or other source of power, and switches 33 to ground. Carried by each car is a contact member adapted to engage a selected one of the rails 21 when the train comes to a stop, this contact member here comprising a wheel 35 journaled in a yoke 36 fixed on the upper end of a pin 37 which is slidably mounted in a bracket 38 carried by the car, a spring 39 normally pressing the wheel upward 10 while a collar 40 on the pin limits the upward movement. From these contact members wires 41 lead to one terminal of each solenoid 10 while from the opposite terminals of the solenoids wires 42 lead to ground. 15 20 Where the doors on opposite sides have to be required to be alternately opened in the course of a run I preferably provide a pair of these contact members spaced on opposite sides of the car as shown in Fig. 2 and 25 arrange the rails 21 at the different stations accordingly. Where the doors on one side only are opened during the entire run a switch may be provided to switch the contacts from one set of door control devices 30 to the other at the end of the run.

The operation is as follows: The switches 33 will be located at suitable points on the station platform and the wires 24 will lead in groups to the different bars 27 according 35 to which section of the train is to have its doors controlled from each individual switch. In the present instance the three cars at one end are controlled by one switch, the four center cars by the second switch, and the three cars at the other end by the 40 third switch. The wires 24 as will be seen, lead in groups of three, four and three to the respective bars 27.

The motorman will bring the train to a 45 stop at a position to have each wheel contact in engagement with the proper rail and when either of the switches is closed the current will flow through the solenoids of the group of cars which are in contact with the rails connected to the bar with 50 which that particular switch is connected. When the switch is opened the springs bring the door operating devices to normal position with the doors closed.

It will be apparent of course that by 55 changing the grouping of the wires upon the bars the number of cars whose doors are controlled by an individual switch may be varied. It will also be understood that the number of the bars 26, together with

their switch controlled connections to ground may be varied as desired.

I claim as my invention:

1. In a car door control system for trains, a contact rail adjacent which a car is adapted to come to rest, car door operating means, means for electrically controlling said car door operating means, including a contact member on the car adapted to engage the said rail, and a hand switch adapted for mounting on a stationary part independent of the car.

2. In a car door control system for trains, a plurality of contact rails under which the cars are adapted to come to rest, electrically controlled car door operating means including a contact member for each car adapted to engage a selected one of said rails when the car is at rest, a plurality of hand switches, and means whereby a closed circuit through a source of power may be established through either of said switches and different groups of said rails, said means including the electrical control means of the cars whose before mentioned contact members are engaging the rails of the said groups.

3. In a car door control system for trains, a plurality of contact rails under which the cars are adapted to come to rest, electrically controlled car door operating means including a contact member for each car adapted to engage a selected one of said rails when the car is at rest, a plurality of hand switches, and means whereby a closed circuit through a source of power may be established through either of said switches and different groups of said rails, said means including the electrical control means of the cars whose before mentioned contact members are engaging the rails of the said group, and means whereby the number of cars in a group may be varied.

4. In a car door control system for trains, a series of contact rails adjacent which the cars are adapted to come to rest, electrically controlled car door operating means, and a hand switch adapted for mounting on a part independent of the train and controlling the car door operating means of the different cars.

In testimony whereof, I have signed my name to this specification in the presence of two subscribing witnesses, this 5 day of September, 1919.

SAMUEL THOMAS WALKUP.
